WRINGER RELEASE MECHANISM

Carl Moon, Detroit, Mich.

Application June 18, 1934, Serial No. 731,075

6 Claims. (Cl. 68—32)

This invention has reference to wringer roll mechanism, particularly to release mechanism therefor, and has for one of its objects provision of a release mechanism capable of being operated by means of an unusual movement of one or both of the wringer rolls relative to each other and the wringer frame.

A further object is to provide means for retaining the upper wringer frame portion upon the lower portion, the retaining means being quickly movable out of retaining position by means of off-setting movement of the roll.

Other objects will appear in the following description and accompanying drawing in which—

Fig. 1 is a side elevational view showing an embodiment of my invention with certain portions broken away to facilitate deposition.

Fig. 2 is a fragmentary detailed view showing movements of a portion of my mechanism to be described.

Fig. 3 is a fragmental view showing detail of structure and operation of a portion of the mechanism shown in Fig. 4.

Fig. 4 is a fragmental outline prospective detail view of a portion of the mechanism to be described.

Fig. 5 is a prospective view showing the parts included in Fig. 4 in dis-assembled position and

Fig. 6 is a sectional view taken from line 6—6 on Fig. 1.

Fig. 1 discloses my invention in combination with a roll wringer mechanism which generally comprises a conventional wringer post designated 10, carrying a driving shaft 11, gears 12 and a driven gear 13.

A lower wringer frame 14 is supported upon the post and is fitted with a removable top frame member 15.

The upright end portions of the lower frame are preferably of hollow construction of a form designated 16 in Fig. 6.

A lower wringer roll 17 is mounted in the frame by means of its shaft 18 journalled in the lower ends of member 19 which are pivotally supported on frame 14 by means of studs 20.

Shaft 18 has driving connection with gear 13 through a flexible coupling 21. The opening in frame 14 through which shaft 18 passes is of such proportions as to permit the shaft to move relative to the frame and the flexible coupling noted permits such movement without alteration of the driving connection.

The upper ends of member 19 are fashioned 55 to have outwardly directed hooks 22 and en-

gaging these are inwardly directed hooks 23 formed on the inner end portions of top frame 15. The function of this will be explained shortly.

An upper wringer roll 24 is journalled in members 25 which are pivotally mounted at 25' upon angulated plate members 26 which have upper horizontal portions 27. Fig. 6 will illustrate that members 26 are so proportioned as to slide vertically within the uprights of frame 14.

A spring member 28 is mounted in the top frame by means of an adjustment screw 29 and has its outer ends resting upon plates 26. The spring is obviously adapted to force the plates, carrying members 25 and roll 24, downwardly to abut lower roll 17. However the spring is not effective except when the top frame is retained in suitable position upon the lower frame which arrangement is accomplished by reason of hooks 22 being engaged with hooks 23 of the top frame.

It will be noted, as best shown in Figs. 4 and 5, that member 19 carries a boss 30 which engages a slot 31 formed in the adjacent side of member 25.

It will also be noted that roll 17 may be swung laterally about the axis of stud 20 and roll 24 about the axis of pivot 25' and that the members are made to operate in unison by reason of stud 30 being engaged in slot 31.

Fig. 2 illustrates the possible movement of member 19, and Fig. 3 illustrates, in solid lines, the relative position of hooks 22 and 23 when the roll is in normal central position. In this position hooks 22 are obviously adapted to retain the top frame in position to hold spring 28 in pressure relation. Swinging movement of the lower roll will displace the hooks as shown in dotted lines, whereby the top frame and pressure will be released.

With the foregoing in mind it will be clear that with parts arranged as in Figs. 1 and 4 the wringer may be operated in conventional manner. If, during this operation the rolls are pushed or pulled out of vertical alignment members 19 and 25 are swung upon their pivots as indicated in Fig. 2 which movement will obviously displace hooks 22, as noted, to release the top frame.

The action described has special utility in the event of accidental insertion of an operator's fingers between the rolls. In such an event an operator would involuntarily jerk or pull away from the mechanism and this movement would

result in immediate release of pressure between the rolls as above described.

While I have here shown an embodiment of my invention, numerous modifications of its structure will be apparent to those skilled in the art. I do not wish to be limited in the matter of structure except within the scope of appended claims.

What I claim is:

1. A roll wringer mechanism having in combination a lower frame, a top frame, upper and lower wringer rolls supported in a manner to be laterally movable with respect to the frames, mechanism connecting the roll supports whereby the rolls are caused to move in unitary direction, tensioning means adapted to maintain the rolls in pressure relation, mechanism connected with the rolls for retaining the same in pressure relation, said mechanism being movable, upon lateral movement of the rolls, to release the tensioning means.
2. A roll wringer mechanism having in combination a lower frame, a movable top frame, upper and lower wringer rolls laterally movable in the lower frame, tensioning means active to force the upper roll into pressure relation with the lower roll, mechanism connected with the lower roll for retaining the tensioning means active, said mechanism being movable, upon lateral movement of the lower roll, to release the tensioning means.
3. In a roll wringer mechanism the combination of a lower frame, a top frame releasably attached thereto, upper and lower wringer rolls pivotally mounted in the lower frame and mechanism connecting the rolls and top frame whereby lateral movement of the rolls in the frame brings about release of the top frame from the lower frame.
4. A roll wringer mechanism having in combination a lower frame, a removable top frame,

upper and lower wringer rolls, said rolls being supported by means of mechanisms pivotally supported in the lower frame whereby the rolls are laterally movable with respect to the frame, said mechanisms having connections with the top frame whereby when the rolls are in one position the top frame is retained upon the lower frame and when the rolls are moved laterally from said position the top frame is released from the lower frame.

5. A roll wringer mechanism having in combination a lower frame, a removable top frame, upper and lower wringer rolls, said lower roll being supported by means of mechanisms pivotally supported in the lower frame whereby the roll is laterally movable with respect to the frame, said mechanism having connection with the top frame whereby when the roll is in one position the top frame is retained upon the lower frame and when the roll is moved laterally from said position the top frame is released from the lower frame.

6. A roll wringer mechanism having in combination a lower frame, a movable top frame, upper and lower wringer rolls, tensioning means in the top frame adapted to force the top frame away from the lower frame, means for retaining the top frame upon the lower frame in opposition to said tensioning means comprising hook members engaging portions of the top frame, said hook members being pivotally mounted in the lower frame in such a manner as to be movable into or out of engagement with the top frame, said members having portions supporting the lower roll in laterally movable relation to the lower frame whereby lateral movement of the roll brings about movement of said hooks in position to retain or release the top frame.
